UNITED STATES PATENT OFFICE.

THEODORE PARKER BROWN, OF WORCESTER, MASSACHUSETTS.

PNEUMATIC OR BELLows FOR MUSICAL INSTRUMENTS.

SPECIFICATION forming part of Letters Patent No. 670,700, dated March 26, 1901.

Application filed December 28, 1900. Serial No. 41,410. (No model.)

To all whom it may concern:

Be it known that I, THEODORE PARKER BROWN, a citizen of the United States, residing at Worcester, in the county of Worcester 5 and State of Massachusetts, have invented certain new and useful Improvements in Pneumatics or Bellows for Musical Instruments; and I do hereby declare the following to be a full, clear, and exact description of the invention, such as will enable others skilled in the art to which it appertains to make and use the same.

My present invention relates to certain new and useful improvements in pneumatics or bellows for musical instruments, and more particularly to operating-pneumatics for self-playing musical instruments.

It is well known to those versed in the art that pneumatics as ordinarily constructed 15 make a snapping noise resembling somewhat the cracking of a whip whenever the air is admitted or thrown into them, which noise is due to the quick straightening out or expanding of the folded portion or portions of the 20 flexible leather of the pneumatic during its movement from a collapsed to an expanded position. This noise is very objectionable, as will be obvious, and is often so loud as to be heard above the tones of the sounding 25 devices, and hence detracts materially from the harmony and tone of the musical instrument.

It is the purpose of the present invention to entirely overcome the above-noted objection 30 and to materially improve the functions and working of the pneumatics and make the same more durable.

Briefly stated, the invention consists in stiffening the leather of the pneumatic at the free surfaces thereof without impairing their 35 flexibility or readiness to fold or work, said 40 stiffening being accomplished by applying to the surfaces of the leather on opposite sides of or slightly removed from the central folding-line a suitable stiffening medium—such, 45 for instance, as glue, paint, shellac, varnish, or some other suitable quick-drying liquid substance or other material.

In order to enable others to understand, 50 make, and use my invention, I will proceed to describe the same in detail, reference be-

ing had for this purpose to the accompanying drawings, in which—

Figure 1 is a perspective view of an operating-pneumatic embodying my invention. Fig. 2 is a sectional view of a portion of a 55 pneumatic, showing the stiffening material applied to the leather.

In the drawings is illustrated an ordinary form of operating-pneumatic such as is now generally employed in connection with self-playing musical instruments, and in said drawings the reference-numeral 1 designates the lower or stationary board of the pneumatic, and 2 the upper or movable board, while the numeral 3 designates the usual 60 bellows portion usually composed of folded leather or rubber-coated fabric that is secured to the sides and end of the upper and lower boards of the pneumatic, said leather or rubber-coated fabric being arranged to 65 fold on a central line 4.

As ordinarily constructed a pneumatic, as 70 above described, makes a snapping or cracking noise when air is thrown thereinto, which is due to the quick straightening-out movement of the folded portions of the flexible 75 leather of the pneumatic, and it is this objectionable noise that I seek to overcome. In accomplishing this object I apply to the surface

of the leather 3 both on the end and on the 80 sides a stiffening agent or medium 5, said stiffening agent or medium being applied over the entire surface of the leather except at the central portions thereof, where the folding

takes place—as, for instance, at the central 85 line 4, as clearly shown in the drawings. This stiffening agent or medium is by preference, owing to its ease of application, composed of some quick-drying liquid substance,

such as glue, paint, shellac, varnish, or other 90 suitable substance or material. The stiffening agent or medium permeates the leather and renders the same stiff at all points except at the lines of folding, which latter remain in their natural flexible state, and thus 95 admit of a free and unimpaired working of the pneumatic.

I do not wish to be understood as limiting myself to the specific stiffening agents or media herein set forth, for it will be obvious 100

that any substance or material may be employed that will render the surface of the leather more or less inflexible or stiff except at the points indicated.

5 In the drawings I have shown the stiffening agent as applied to the outer surfaces of the pneumatic; but it may be applied on the inner surface, if desired. I have also shown the stiffening agent applied to the sides and 10 also to the end of the foldable portions of the pneumatic; but I wish it understood that I may omit the application of said agent to the sides and apply it to the end only at the points indicated without departing from the 15 spirit of the invention.

What I claim is—

1. A pneumatic having the foldable portion thereof formed of flexible material, said material being stiffened on opposite sides of a 20 folding-line.

2. A pneumatic having the foldable portion

thereof formed of flexible material, said material being coated with a stiffening agent or medium on opposite sides of the folding-line.

3. A pneumatic having the foldable portion 25 thereof coated with a liquid stiffening agent or composition, said agent being applied to the surface of the bellows on opposite sides of the folding-line.

4. A pneumatic having the flexible folding 30 portions thereof coated with a liquid stiffening agent, said agent being applied to the surface of the said folding portions on opposite sides of the lines of fold, said lines being uncoated.

In testimony whereof I affix my signature in presence of two witnesses.

THEODORE PARKER BROWN.
